United States Patent

Des. 234,385
Patented Feb. 25, 1975

234,385

BED

Raymond R. Turner, Morristown, Tenn., assignor to Ludlow Corporation, Needham Heights, Mass.

Filed Apr. 25, 1973, Ser. No. 354,333

Term of patent 7 years

Int. Cl. D6—01

U.S. Cl. D6—80

FIG. 1

FIG. 3

FIG. 1 is a front and left side perspective view of a bed showing my new design with the right drawer in partially opened condition, the rears of the head and foot boards being substantially the same as the fronts thereof;

FIG. 2 is a left side elevational view, the right side being a mirror image thereof; and

FIG. 3 is a front elevational view.

I claim:

The ornamental design for a bed, substantially as shown and described.
